(57) **CLAIM**

The ornamental design for a bracket for fixing communication equipment, as shown and described.

DESCRIPTION

FIG. 1 is a perspective view of a bracket for fixing communication equipment, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is another perspective view thereof, as shown in an environment of use.

The broken lines are for environmental purpose only and form no part of the claimed design.

The jagged uneven broken lines indicate an omission boundary and form no part of the claimed design.
